UNITED STATES PATENT OFFICE.

HENRI COLNOT, OF PARIS, FRANCE.

INTERNAL-COMBUSTION ENGINE.

Application filed April 26, 1922. Serial No. 556,698.

To all whom it may concern:

Be it known that I, HENRI COLNOT, a citizen of the Republic of France, and residing at Paris, Seine Department, No. 17 Rue 5 Rochechouart, in the Republic of France, engineer, have invented certain new and useful Internal-Combustion Engines, of which the following is a specification.

My invention relates to an internal combustion engine and particularly to a new valve gear arrangement for four-cycle engines. The essential characteristic of the invention consists in the fact that the usual valves are replaced by spheres or balls, thus 15 simplifying the construction of the valve itself, the valve seat and the controlling means. In particular, the use of gears for valve operation can be obviated.

The accompanying drawing shows by way 20 of example a form of construction of an engine according to the invention.

Fig. 1 is a vertical section.

Fig. 2 is a horizontal section on the line A—A Fig. 1.

25 Figs. 3 and 4 are plan views of the details of the valve control devices.

1 is the engine cylinder provided with a water jacket and having movable therein the piston 2 actuating the crank shaft 3. The 30 admission port 4 and exhaust port 5 are each adapted to be opened and closed by a ball 6 which is entirely free and is actuated by a push-piece 7 having a reciprocating motion and slidable in a guide-way 8. The ball rests 35 on the top of the said push-piece 7 solely by its own weight. When the push-piece 7 rises it lifts up the ball and presses the same upon its seat, acting in the rear of the latter so that no movement can take place as long as 40 the valve is required to be kept closed. To open the valve, the push-piece 7 descends and the ball will now fall by its own weight either for the admission of fresh gas or for the escape of burnt gas.

45 When the ball has thus fallen, the gas passage is entirely free and the flow will take place in a direct manner and without change of direction between the admission or exhaust passage and the cylinder, which is a 50 favourable circumstance, since losses of pressure are attended by corresponding losses of energy.

The balls are actuated through the intermediary of a cam shaft 9, and to obviate as 55 much as possible all drive by means of gearing, the cam shaft is actuated from the

power shaft 3 by a connecting rod 10. The shaft 9 rotates at the same speed as the power shaft 3, but as the present case relates to a four-cycle engine, the actuating 60 elements should be so constituted that each valve shall only open at every alternate revolution of the power shaft or the cam shaft.

For this purpose the shaft 9 is provided 65 with a cam 11 acting on a bell-crank 12 which is pivoted to a fixed axle 13 and whereof the roller 14 is pressed against the profile of the cam by a spring 15. The opposite end of this lever ends in a fork 16. 70 The push-piece 7 is secured to the end of a rod 17 slidable in a lug 18 secured to the crank-case. A spring 19 disposed between the lug 18 and the push-piece 7 tends to hold the latter in the raised position. 75

Upon the lower end of the rod 17 is slidable and revoluble the sleeve 20 whose outer surface is provided with three ribs 21 extending throughout the whole length of the said sleeve. The latter is slidable in the 80 hub of a gear wheel 22 disposed between two bearings 23 which prevent the lengthwise movement of the same. The teeth of the said gear wheel engage the threaded portion of a cam 24 of special shape which acts 85 as a worm in cooperation with the gear wheel 22. The threads of the cam 24 are straight upon the greater part of the profile and thus form approximately circular 90 grooves 25 connected together by a passage 90 26 having the shape of a screw-thread whereby the said gear wheel shall be given an intermittent rotary motion and will rotate by one-sixth of a revolution for each revolution of the shaft 9. The fork 16 of 95 the bell-crank 12 is so disposed as to bear at times upon the end of the ribs 21 or at other times in the spaces between the said ribs.

The operation of the said mechanism is as follows:

Under the action of the cam 11 and spring 15, the bell-crank 12 will oscillate once in either direction for each revolution of the driving shaft. But the valve should only open at every other revolution of the power shaft, as is required for the four-cycle engine. When the valve is to be opened, the sleeve 20 with the ribs 21 should be in the position shown in Fig. 4. The fork 16 of the bent lever is caused to bear upon the 110 end of two ribs and it lowers the sleeve 20, which latter draws the push-piece 7 by

means of the stop-piece 27. The ball 6 now falls by its own weight and opens the port. For exceptional speeds, the said ball could be caused to descend with the push piece if 5 so desired, by suitable means such for example as a spring driving the ball downwards, or by an extension of the push piece disposed above the ball, or the like.

The valve is closed by the spring 19 10 which raises the push-piece 7 and the ball as soon as the cam 11 permits this action. When the valve is to remain closed, either during the compression, explosion and exhaust in the case of the admission valve, or 15 during the suction, compression and explosion in the case of the exhaust valve, the sleeve 20 should occupy the position shewn in Fig. 3. In this position, one of the ribs 21 can engage between the branches of the 20 fork 16 so that the oscillation given to the bell-crank 12 by the cam 11 during the second revolution of the power shaft can take place without acting on the sleeve 20, thereby leaving the ball 6 in the closed position. 25 The cam 24 mounted on the shaft 9 serves precisely to place the sleeve 20 in the two desired positions. The latter is provided with three ribs in the present case, and therefore the fractional parts of a rotation 30 should have the value of one-sixth of a rotation. When the wheel 22 contains twelve teeth, the cam 24 should have a double thread. As long as the teeth of the wheel 22 engage the straight parts of the 35 thread, the wheel and the sleeve will remain fixed. During this period at the moment of opening the valve, the bell-crank acts upon the sleeve, and during the closing of the valve it oscillates freely. 40 The oblique portions 26 of the cam act upon the teeth of the wheel 22 only at the moment when the roller 14 reaches the base of the cam, that is to say when the sleeve 20 and lever 12 are at the end of the up 45 stroke. The wheel 22 now rotates rapidly, and it stops when the cam 11 again acts upon the lever 12. It is obvious that the invention is not limited to the embodiment hereinbefore described, and that the principle 50 as set forth can be carried into effect by the use of all adequate means, without departing from the nature of the invention.

In particular, any suitable mechanism other than the one described may be used 55 to actuate the push-piece only once in two revolutions of the engine.

Claims:

1. In an internal combustion engine, a power cylinder, a piston, engine valves, 60 seats formed in the walls of the cylinder cooperating with the said valves, the valves being constituted by spherical balls, and means for controlling the said balls.

2. In an internal combustion engine, a power cylinder, a piston, engine valves con- 65

stituted by spherical balls, seats formed in the walls of the cylinder and cooperating with the said balls, a push-piece for each ball having a reciprocating motion and comprising an inclined plane adapted to 70 impel the ball upon its seat and to hold it in this position, and a lateral guide for the said push-piece against which the latter is caused to bear in order to hold the said ball in the fixed position against the 75 internal pressure.

3. In an internal combustion engine, a power cylinder, a piston, engine valves constituted by balls, seats formed in the walls of the cylinder and cooperating with the said balls, a push-piece for each ball having a reciprocating motion and adapted to 80 impel the ball upon its seat and to hold it in this position, the said engine valves being adapted to open by the action of gravity when the respective push-pieces are lowered, thereby completely opening the direct passages between the valve-seats and the respective orifices, the cylinder being 85 provided with admission and exhaust orifices situated exactly opposite the said seats, each push-piece being moved in a transverse direction to the flow of gas between the seat and the respective orifice, and each ball being free to move in the 90 transverse direction as well as in the direction of this flow, for the purpose set forth.

4. In an internal combustion engine, a power cylinder, a piston, engine valves constituted by balls, seats formed in the walls of the cylinder and cooperating with the said balls, a push-piece for each ball having a reciprocating motion and adapted to 100 impel the ball upon its seat and to hold it in this position, the cylinder being provided with admission and exhaust orifices opposite and on a level with the said seats, the push-pieces being guided in a substantially vertical direction, the said engine valves being adapted to open by the action of gravity when the respective push-pieces are lowered, thereby completely opening the direct passages between the valve-seats and the respective orifices, the cylinder being 105 provided with admission and exhaust orifices situated exactly opposite the said seats, each push-piece being moved in a transverse direction to the flow of gas between the seat and the respective orifice, and each ball being free to move in the transverse direction as well as in the direction of 110 this flow, for the purpose set forth.

5. In an internal combustion engine, a power cylinder, a piston, engine valves constituted by balls, seats formed in the walls of the cylinder and cooperating with the said balls, a push-piece for each ball having a reciprocating motion and adapted to 115 impel the ball upon its seat and to hold it in position, a sleeve disposed upon the end of the 120

said push-piece farthest from the said ball, the said push-piece being provided with longitudinal ribs and having an intermittent rotation, a lever oscillating at regular intervals, a fixed axle having the said lever mounted thereon, the latter being adapted to bear at times upon the grooves of the said sleeve for opening the valve, and at other times to engage in the spaces between the 10 said ribs while the said valve is closed.

6. In an internal combustion engine, a power cylinder, a piston, engine valves constituted by balls, seats formed in the walls of the cylinder and cooperating with the 15 said balls, a push-piece for each ball having a reciprocating motion and adapted to impel the ball upon its seat and to hold it in position, a sleeve disposed upon the end of the said push-piece farthest from the said

ball, the said push-piece being provided with 20 longitudinal ribs and having an intermittent rotation, a lever oscillating at regular intervals, a fixed axle having the said lever mounted thereon, a gear wheel in whose hub the said sleeve is adapted to slide, a cam 25 adapted to actuate the said gear wheel, a shaft actuated by the engine and having the said cam mounted thereon, the latter being provided with threads forming on part of the profile grooves of approximately circular shape which are connected together by 30 grooves of screw-thread form.

In testimony that I claim the foregoing as my invention, I have signed my name in presence of a subscribing witness.

HENRI COLNOT.
